Primary Examiner — Caron D Veynar*Assistant Examiner* — Martie K Holtje(74) *Attorney, Agent, or Firm* — George R. McGuire; Bond Schoeneck & King PLLC(57) **CLAIM**

The ornamental design for a flying toy, as shown and described.

DESCRIPTION

FIG. 1 is an upper, front perspective view of a flying toy showing my new design;

FIG. 2 is an upper, rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a lower, front perspective view thereof.

The structure depicted by broken lines has been shown for the purpose of illustrating portions of the flying toy that form no part of the claimed design.
